UNITED STATES PATENT OFFICE.

RAYMOND C. RUPP, OF KENDALLVILLE, INDIANA.

CLOSED AUTOMOBILE BODY.

Application filed December 18, 1922. Serial No. 607,648.

To all whom it may concern:

Be it known that I, RAYMOND C. RUPP, a citizen of the United States, residing at Kendallville, in the county of Noble and 5 State of Indiana, have invented certain new and useful Improvements in Closed Automobile Bodies; and I do declare the following to be a full, clear, and exact description of the invention, such as will enable others 10 skilled in the art to which it appertains to make and use the same.

My invention relates to improvements in closed automobile body attachments adapted for connection to touring car or roadster 15 bodies, the attachment being provided with vertically slidable curtains, horizontal guides for these curtains when raised, and vertical guides at the sides of the body to receive the curtains when they are lowered. 20 One object of the invention is to provide for pivotally mounting one of the guides which extends vertically, whereby this guide may be swung outwardly when the subjacent automobile door is opened, giving ample room for entering or leaving the 25 machine. In this connection, a further aim is to connect the guide in question with the door so that opening of this door will open said guide without further operations.

Another object of the invention is to provide guides of novel construction to receive the curtains when raised and to guide the curtains at opposite sides of the body into overlapping relation between the usual 30 top covering and the lining.

With the foregoing in view, the invention resides in the novel subject matter herein-after described and claimed, the description being supplemented by the accompanying 35 drawings.

Figure 1 is a side elevation of a portion of a well known form of automobile, showing the application of my invention thereto.

Figure 2 is a side elevation of one of the 40 flexible frames to which the curtain coverings and their transparent panels are secured.

Figure 3 is an elevation of one of the curtains complete.

Figure 4 is a vertical transverse sectional view with the curtains raised into overlapping relation.

Figure 5 is a detail vertical section showing one of the curtains lowered.

Figure 6 is a detail longitudinal sectional view on an enlarged scale.

Figure 7 is an outer side elevation of the outwardly swinging curtain guide.

Figure 8 is an edge view of the guide shown in Fig. 7.

Figure 9 is an inner side elevation of the 60 guide illustrated in Figs. 7 and 8.

Figure 10 is a detail horizontal section on line 10—10 of Fig. 7.

Figure 11 is a perspective view of the 65 bearing for the upper pivot pin of the outwardly swinging curtain guide.

In the drawings above briefly described, the numeral 1 designates a closed body attachment to be mounted on the body 2 of a 70 well known touring car or roadster, a touring car attachment being shown. This attachment is provided with a pair of flexible vertically slidable curtains 3 at each side, suitable vertical guides 4 being provided for 75 all edges of the curtains except one, in the present showing, this being the front edge of the right hand front curtain 3 which is above the forwardly opening front door 5 of the body 2. The guide for this edge of the 80 door is indicated on the drawings by the reference character 6 and it is so mounted that it may be swung outwardly when the curtain is raised sufficiently to clear said guide, thus giving a great deal more room for entering 85 and leaving through the front door, than would otherwise exist.

The guide 6 is preferably formed from wood, suitably covered to give an attractive appearance, the front edge of said guide being suitably shaped to engage the windshield 90 7, while the rear edge of said guide is suitably rabbeted as indicated at 8 to accommodate the curtain, a strip of metal 9 being secured to said edge to co-operate with the rabbeted 95 portion thereof, in forming a channel-shaped guiding means for the front edge of the curtain. In the construction shown, the upper end of the guide 6 is provided with a pivot pin 11 which is engaged with a suitable 100 bearing 12 (Figs. 1 and 11) carried by the top of the body attachment. The lower end of the guide 6 is provided with an attaching plate 13 through which suitable fasteners 14 are passed to connect it with the door 105

5. In the construction shown, the plate 13 is resilient to some extent, in order to permit simultaneous outward swinging of the door 5 and the guide 6, even though the pivot 11 is not in direct alignment with the hinges 110 of said door.

The top of the attachment is provided

with transverse bows 15, two of which have been shown in Fig. 6, the vertical curtain guides being disposed at the ends of the inner opposed sides of these bows. To guide 5 the curtains at opposite sides of the body, when they are raised, I secure upper and lower metal strips 16 and 17 to the upper and lower sides of the bows 15, said strips extending to the vertical curtain guides and 10 projecting beyond the inner opposed sides of the bows to receive the edge portions of the curtains therebetween. At suitable points, the lower strips 17 are stamped upwardly or otherwise formed, to provide 15 a pair of cams 18 which are spaced apart transversely of the machine and have outwardly declining surfaces. When the curtains at opposite sides of the body are raised, they encounter the cams 18 and are 20 thus effectively guided into the overlapping relation shown in Fig. 4. If desired suitable snap fasteners or the like 19 may be provided at the ends of the curtains for holding them in either raised or lowered positions, as will be seen by reference to Figs. 3, 4 and 5.

It is to be understood that the bow-carried guiding strips 16 and 17 are positioned between the usual top covering 20 and the lining 30 which it is customary to provide on the inner sides of enclosed bodies, this lining however being omitted from the drawings.

While the curtains 3 may be of any desired construction which will permit them 35 to yield in passing from vertical to horizontal positions and vice versa, I prefer to provide the construction shown in Figs. 2 and 3. In these views, the numerals 21 designate a pair of spring metal side strips 40 connected at appropriate intervals by rigid horizontal bars 22, the curtain covering being suitably stitched around these bars and being provided with flexible transparent panels 23.

45 From the foregoing, it will be seen that excellent results may be obtained from the details disclosed. These details are therefore preferably followed, but it is to be understood that within the scope of the invention as claimed, numerous minor changes 50 may be made.

I claim:

55 1. A closed automobile body having a doorway, a door in the doorway, a vertically movable curtain above the door, horizontal guides under the top of the body for receiving said curtain when raised and moved to an inoperative position, a vertical guide at one side of the doorway for engaging one edge of the curtain when lowered, and a second vertical guide for the other edge of the curtain positioned at the

opposite side of the doorway, said second vertical guide being positioned at the hinge side of the doorway and having its upper 65 end mounted for turning movement and its lower end connected with the door to cause movement of the guide with the door when the curtain is raised to the inoperative position above said guides. 70

2. A closed automobile body, opposed side curtains slidable from a vertical operative position to a horizontal inoperative position beneath the top, and sets of horizontal guides for engaging the curtains and supporting the curtains in the horizontal position with the inner end portions of the curtains in overlapping relation, said sets of guides including lower strips extending beneath the curtain and having 80 cam portions for guiding the curtains into overlapping relation. 85

3. The structure of claim 2 having the lower guide strips bent to provide portions extending inwardly and upwardly to form the cams. 90

4. A closed automobile body having a pair of transverse parallel top bows, opposed vertical curtain guides at each side of the body whose upper ends terminate at the ends of the inner opposed sides of said bows and flexible curtains at the body sides engaged with said guides; and upper and lower metal strips secured to the upper and lower sides of said bows respectively and extending beyond said inner opposed sides of said bows, said strips extending to said curtain guides to receive the curtains when raised, the lowermost of said strips having cams for guiding the curtains into overlapping relation with each other when raised. 95

5. A structure as specified in claim 4; said cams consisting of upwardly stamped portions of the projecting edges of said lowermost strips. 100

6. A closed automobile body, vertical curtain guides at the sides of said body, opposed side curtains slidably engaging said guides and movable from a vertical operative position beneath the top of said body, and sets of horizontal guides for engaging the curtains when the curtains are moved to the inoperative position and supporting the curtains with the inner end portions of the curtains in overlapping relation, each set of guides including upper and lower strips with the lower strips provided with cams for guiding the curtains into overlapping relation. 115

In testimony whereof I have hereunto affixed my signature.

RAYMOND C. RUPP.
